UNITED STATES PATENT OFFICE.

RALPH D. GARDNER, OF BELOIT, WISCONSIN, ASSIGNOR OF ONE-THIRD TO EDWARD B. GARDNER AND ONE-THIRD TO JOHN NIELSEN.

GRINDING MACHINE.

Original application filed April 10, 1922, Serial No. 551,008. Divided and this application filed June 28, 1923. Serial No. 648,217.

This invention pertains to grinding machines and the present application constitutes a division of my pending application, Ser. No. 551,008, filed April 10, 1922.

One of the primary purposes of my present invention is to provide for accurate dressing of the faces of the grinding wheels, and with this end in view, my invention contemplates the provision of a wheel dresser, and a novel mounting therefor whereby the dresser may be positioned in proper relation to the wheels to insure that they be uniformly and accurately dressed.

Another object is to provide an adjustable abutment for limiting the approaching movement of the grinding tools so that they will be accurately positioned with relation to the wheel dresser whenever the dressing operation is performed.

Other objects and advantages of this invention should be apparent as the same becomes better understood by reference to the following description, when considered in connection with the accompanying drawings.

Referring to the drawings:

Fig. 1 is a rear elevation of a machine embodying my invention;

Fig. 2 is an end elevation looking toward the left at Fig. 1;

Fig. 3 is a fragmentary plan view of the wheel dresser mounting; and

Fig. 4 is a vertical sectional view taken on line 4—4 of Figure 3.

By reference to the drawings it will be observed that the machine comprises essentially a frame or base portion 4 upon which the various operating mechanisms are mounted, as will be later explained. The upper face of the frame at each side of the center thereof is shaped to provide a guideway 5, and upon each of these guideways there is reciprocably disposed a carriage 6 provided with suitable bearings in which the wheel carrying shafts 7 are respectively journaled. Upon the inner end of each of these shafts there is mounted a grinding wheel 8. The shafts may be equipped with driving pulleys 9, or driven by individual motors, if preferred.

The carriages 6, with the grinding tools mounted thereon, are moved toward and from each other by suitable mechanism operated from a rock shaft 11, which is nor-

mally urged in one direction to cause an approaching movement of the grinding wheels by an arm 10 fixed thereto and actuated by a weight 10' suspended therefrom. The rock shaft is equipped with a pinion 12 meshing with a rack 13, carried by one of the carriages 6, and with a rack bar 14 pivotally connected with the other carriage, as will be apparent from Fig. 1.

The shaft 11 is rocked in a clockwise direction, viewing Fig. 1, to move the grinding tools apart, by means of a cam 15 (Fig. 2) fixed upon a continually rotating shaft 16 and engaging a stud 17 projecting laterally from an arm 18 fixed on the shaft 11, but at the opposite side of the machine from the arm 10. Manual actuation of the shaft against the action of the weights 10' may be effected when desired by means of a hand lever 19, fixed on the shaft 11 adjacent to the arm 18. The shaft 16 is driven from a train of gearing to which power is transmitted through a drive-shaft 21 from a variable speed pulley 22 driven by a belt in the usual manner. The approaching movement of the grinding tools during normal operation of the machine, is limited by an abutment bar equipped with a micrometer adjustment, all as explained in my prior application, previously mentioned.

For the purpose of dressing the faces of the wheels when such becomes necessary, I have mounted at the rear of the machine upon a bracket 23 a standard 24 carrying a wheel dresser rod 25, which is provided at its forward end with a wheel dresser 26 projecting at one side of the rod and normally disposed outside the perimeter of the grinding wheels 8, as shown in Fig. 2. When dressing of the wheels becomes necessary, the rod 25 is slid longitudinally forward to dispose the wheel dresser between the wheels and in position to engage and operate upon the face of one of the wheels. It will be observed from Fig. 4 that the rod 25 is provided with longitudinally extending grooves 27 and 28, in which a pin 29 is engaged to prevent rotation of the rod. When one of the wheels has been dressed, the pin 29 is withdrawn, the rod 25 is given a half turn to oppose the dresser 26 to the face of the other wheel, whereupon the pin 29 is inserted into the groove 28, thereby locking the dresser in position.

In order that the dresser may be adjusted to dispose it in proper alignment with the face of the wheel to be dressed, the standard 24 is adjustably mounted upon the bracket 23, and as will be apparent from Fig. 3, the adjustable mounting comprises a fulcrum pin 31 projecting upwardly from the bracket into a socket in the standard, and a pair of bolts 32, also projecting upwardly from the bracket through slots 33 formed in the standard. The bracket is also provided forwardly of the standard with a pair of upwardly extending ears or lugs 34, each of which is equipped with an adjustable screw 15 35 bearing against the forward face of the standard. When adjustment of the dresser is required, the bolts 32 are loosened, whereupon by turning the screws 35 in the requisite direction, the standard may be swung 20 in a horizontal plane about the fulcrum pin 31 as a center to properly align the dresser with the wheels to be dressed, whereupon the bolts 32 are again tightened to lock the dresser in its adjusted position. In order 25 to permit the introduction of the dresser into position between the wheels, the wheels are first backed off or separated, and when the dresser has been properly positioned, they are permitted to approach until that 30 wheel toward which the dresser is faced is disposed in position to be operated upon.

For the purpose of limiting the approaching movements of the wheels, so that the one being operated upon will be disposed in just 35 the proper relation with respect to the dresser, there is mounted upon the shaft 11 an arm 36 provided at its outer end with an adjustable abutment screw 37 disposed in vertical alignment with an abutment shoulder 38 upon the machine frame. Since the arm and the wheel carriages are both connected with the shaft 11, it will be apparent 40 that the approaching movement toward the dresser of a wheel to be operated upon will be limited by engagement of the screw 37 with the shoulder 38 on the frame. By adjusting this screw, the approaching movement may be limited to a fine degree of nicety, and if the dresser is positioned in 45 exact alignment with the faces of the wheels to be dressed, and exactly midway between them as it should be, when one of the wheels has been dressed, the dresser is reversed to 50 operate upon the other wheel, and this wheel will likewise be dressed exactly like the first since the approaching movement of this wheel to the dresser will likewise be controlled by the previously adjusted screw 37.

The arm 36 is preferably clamped to the 60 shaft 11, and if during normal grinding operation of the machine it be desirable that the wheels approach more closely together, than is desirable for dressing purposes, the arm may be loosened from the

shaft so that it will not interfere with this 65 approaching movement. During the dressing operation the clutch through which power is transmitted to the machine to reciprocate the dressing wheels, is thrown out so that no reciprocation of the wheels 70 takes place, but the wheels will be revolved for dressing purposes by power applied to their respective driving pulleys 9.

The details of construction illustrated and described are obviously capable of considerable modification without departing from the spirit of the invention, as defined in the following claims.

I claim:

1. In a grinding machine having opposed grinding wheels movable toward and from one another, means arranged adjacent said wheels for wheel dressing purposes and adapted to be moved into the normal path of movement of said wheels, and means for 85 limiting movement of one of said wheels toward the said wheel dressing means during a wheel dressing operation.
2. In a grinding machine having a grinding wheel normally movable toward and from an operating position, a wheel dresser mounted to one side of the axis of said wheel and movable into the path of movement thereof, and adjustable means for restricting the normal movement of said wheel toward said operating position when said dresser is moved into the path of normal movement thereof.
3. In a grinding machine having opposed grinding wheels normally movable toward and from adjacent operating positions, a wheel dresser mounted adjacent said operating positions and to one side of the axis of one of said wheels and movable into the path of normal movement of each wheel and means for restricting the normal movement of said wheels toward said operating positions when said dresser is moved into the path of normal movement thereof.
4. In a grinding machine, the combination 110 of a frame, a pair of carriages slidably mounted thereon, a grinding wheel mounted on each carriage, mechanism normally operative to simultaneously move said carriages toward and from each other, dresser means common to both of said wheels and movable into wheel dressing relation with respect to the wheel faces to be dressed, and an adjustable abutment independent of said wheels 115 for limiting the approaching movements of said wheels for wheel dressing purposes.

5. In a grinding machine, a combination 120 of a pair of grinding wheels, means, for moving said wheels toward and from each other, a wheel dresser arranged for operative engagement with either wheel for dressing the grinding faces thereof, and an auxiliary adjustable stop mechanism independent of said

wheels whereby the approaching movement of said wheels may be adjustably regulated for wheel dressing purposes.

6. In a grinding machine, the combination of a pair of grinding wheels, carriages upon which said wheels are mounted, a rock shaft, connections between said rock shaft and said carriages whereby the wheels are moved toward and from each other upon actuation 10 of said shaft, a weight normally urging said shaft in one direction to cause the approach of said wheels, a cam for actuating said shaft to cause the separation of said wheels, an arm normally loosely mounted on said shaft but adapted to be clamped thereto, and an adjustable abutment screw carried by said arm whereby the approaching movement of said wheels may be limited for wheel dressing purposes.

7. In a grinding machine, the combination of a pair of co-axially arranged grinding wheels, means for moving said wheels toward and from each other, a wheel dresser mounted at one side of said wheels and adapted to be moved into operative position 25 between said wheels, and adjustable means for determining the position of said wheels on their movement toward said dresser when the latter is between said wheels.

8. In a grinding machine, the combination of a frame, a pair of grinding wheels slidably mounted in carriages thereon, means for moving said carriages toward and from each other, a wheel dresser supporting 30 bracket disposed at one side of said frame, a wheel dresser carried by said bracket and adapted to be moved into operative position

between said wheels, and an adjustable stop mechanism cooperative with frame and said means whereby the position of said wheels 40 may be regulated for wheel dressing purposes.

9. In a grinding machine, the combination of a frame, a pair of grinding wheels rotatable in opposed parallel planes on said 45 frame, a bracket on the frame, a standard supported upon said bracket, a wheel dresser carried by said standard and moveable transversely across the opposed faces of 50 said wheels, and means including a fulcrum pin and a pair of adjusting screws whereby the position of said standard with respect to said wheels may be adjusted.

10. In a grinding machine, the combination of a frame, a pair of grinding wheels 55 mounted on said frame, a standard, a fulcrum pin about which said standard may be adjusted in a horizontal plane, a horizontally disposed rod having a plurality of grooves and slidably and rotatably mounted 60 in said standard for movement across one of the opposed faces of said wheels, a wheel dresser carried by said rod, a removable pin adapted to engage each of said grooves to lock said rod against rotation, said grooves 65 being so arranged in said rod that upon removal of said pin from said grooves the rod may be rotated to points where said dresser will engage either wheel and be locked thereat by said pin against rotation, and means for locking said standard in ad- 70 justed position.

RALPH D. GARDNER.
